UNITED STATES PATENT OFFICE

JESSE G. KING, OF DAYTON, OHIO, ASSIGNOR, BY MESNE ASSIGNMENTS, TO FRIGID-AIRE CORPORATION, A CORPORATION OF DELAWARE

REFRIGERATING APPARATUS

Application filed December 31, 1927. Serial No. 243,989.

This invention relates to refrigerating apparatus and particularly to devices for freezing small blocks of ice for table use.

One of the objects of the invention is to provide an improved refrigerating apparatus in which a large quantity of small blocks of ice may be quickly frozen.

Another object is to provide a compact and efficient apparatus which has a large freezing capacity.

Still another object of this invention is to provide such an apparatus in which at least a portion of its capacity may be frozen very quickly.

Further objects and advantages of the present invention will be apparent from the following description, reference being had to the accompanying drawings, wherein a preferred form of embodiment of the present invention is clearly shown.

In the drawings:

Fig. 1 is a view partly in section and partly in elevation of a refrigerating cabinet constructed in accordance with the invention;

Fig. 2 is a section of the cabinet on the line 2—2 of Fig. 1; and

Fig. 3 is a section on the line 3—3 of Fig. 2.

In accordance with my invention I provide a refrigerating cabinet generally denoted by 10 which may be of any suitable or known construction having a large opening 11 which may be closed by a door 12. Within the cabinet are disposed three or more refrigerating elements or evaporators each of which preferably includes a header 12 forming a reservoir for liquid refrigerant and a number of loops of conduit 13 for circulating refrigerant about one or more freezing compartments 14. The freezing compartments preferably consist of a metal shield or pocket in which is inserted one or more containers 15 of any known construction for freezing ice in small blocks or cubes for table use, such as is well known in the art. In the example shown in the drawings six individual compartments each holding a container or tray 15 are included in each evaporator. The loops of conduit 13 are each asymmetrical with respect of the central vertical plane of the header and compartments, and alternate

loops are reversed along the length of the header to provide two sets of ducts 16 adjacent the freezing compartment and two sets of ducts at a distance from the compartment.

The purpose of this arrangement is to facilitate the assembling of compartments in intimate thermal contact with the ducts 16. Under quantity production conditions it is difficult to manufacture a large number of compartments and loops of pipe each of sufficiently constant width to fit snugly together on both sides of the compartment. And if after a number of loops are assembled they do not fit the compartments, it is difficult to compress or expand them to fit exactly. By making the loops wider than the compartments and alternating them along the length of the header, as shown in Figs. 1 and 2, it is a comparatively simple matter to get all of the loops in intimate thermal contact with both sides of the compartment for it is a relatively easy matter to displace a whole loop 13 so as to bring its ducts 16 in contact with the compartment. Preferably the ducts 16 are soldered to the sides of the compartment.

The evaporators are assembled in the cabinet in staggered relation so that the projecting ducts 17 on one evaporator lie between the ducts of its adjacent evaporator. Preferably the loops 13 are placed in groups of two as indicated in Fig. 3 and the groups are separated by spaces sufficiently wide to receive a duct 17. In this case when the evaporators are assembled, as shown in Figs. 2 and 3, the ducts 17 projecting from one evaporator are placed in contact with the compartments of the adjacent evaporator. In this manner each of the evaporators can be economically formed with refrigerant ducts in intimate contact with both sides of its freezing compartment and the ducts of one evaporator which projects from it are in contact with the adjacent evaporator.

It will be noted that the central evaporator 20 is flanked or surrounded by the two side evaporators 21. Consequently, the heat leakage thru the side walls of the cabinet is taken up substantially entirely by the two side evaporators, leaving the full capacity of the central evaporator available for freezing

ice. Consequently, this central evaporator will freeze ice faster than the two side evaporators and a considerable portion of the capacity of the cabinet will thus be frozen in a short time.

The evaporators are supported in the cabinet by individual cradles, each including a pair of straps 30 secured to longitudinal spacing members 31, the cradles being supported by being bolted to hangers 32. The hangers are in turn secured to supporting members 33 which may be secured together and suitably spaced by longitudinal spacers 34. The cradles for each individual evaporator are staggered as shown best in Fig. 2, so as to offset one evaporator with respect to the others in order to bring the loops of the conduits 17 between the loops of the adjacent evaporators. The supports 33, longitudinal spacers 34 and hangers 32 are all secured together to form a unitary frame which may be supported in the cabinet by resting upon the top edge of the side walls 35 and may be secured thereto by any suitable means, such as screws 36. After this frame has been placed in the cabinet in the manner described the top wall 37 may be placed on the side walls of the cabinet and secured in the usual manner.

Refrigerant is circulated thru each of the evaporators in parallel thru inlet connections 38 and outlet connections 39 and is maintained at a constant level by a suitable float valve. The valve and circulating apparatus may be, for example, as shown in the patent to Osborn, No. 1,556,708, October 13, 1925.

Below the evaporators are placed a number of drawers or containers 40 in which the ice frozen in the small containers 15 may be stored. The evaporators and the storage drawers occupy substantially the entire space within the cabinet. Preferably each of the storage drawers is surrounded by a shield 41 for protecting the contents of the drawers from water dripping from the evaporators during periods of defrosting.

While the form of embodiment of the present invention as herein disclosed, constitutes a preferred form, it is to be understood that other forms might be adopted, all coming within the scope of the claims which follow.

What is claimed is as follows:

1. Refrigerating apparatus comprising in combination, a cabinet and a plurality of refrigerating elements disposed side by side in the cabinet; each of the elements including a freezing compartment, a plurality of ducts for circulating refrigerant in intimate thermal contact with the compartment and a plurality of ducts disposed remote from the compartment, the remote ducts in one element being placed between the ducts of the adjacent element which are in intimate contact with the compartment.

2. Refrigerating apparatus comprising in combination, a cabinet and a plurality of re-

frigerating elements disposed side by side in the cabinet; each of the elements including a freezing compartment, a plurality of ducts for circulating refrigerant in intimate thermal contact with the compartment and a plurality of ducts disposed remote from the compartment, the remote ducts in one element being placed in contact with the compartment of an adjacent element.

3. Refrigerating apparatus comprising in combination, a cabinet and a plurality of refrigerating elements disposed side by side in the cabinet; each of the elements including a freezing compartment and a plurality of loops of refrigerant conduit, said loops being wider than the compartment and each loop having a duct in contact with the side of the compartment and a duct remote from the other side of the compartment said remote ducts of one element being placed between those ducts of the adjacent element which are in contact with the compartment thereof.

4. Refrigerating apparatus comprising in combination, a cabinet and a plurality of refrigerating elements disposed side by side in the cabinet; each element including a freezing compartment and a plurality of loops of refrigerant conduit, said loops being wider than the compartment and each of the loops having a duct in intimate contact with one side of the compartment and a duct spaced at an interval from the other side of the compartment, the contacting ducts and the remote ducts being alternated along the length of the compartment and the remote ducts of one compartment being placed between the contacting ducts of an adjacent compartment.

5. Refrigerating apparatus comprising in combination, a cabinet and a plurality of refrigerating elements disposed side by side in the cabinet; each of the elements including a freezing compartment and a plurality of ducts for circulating refrigerant spaced along the compartment, some of the ducts of one element being placed in heat exchange relation with the compartment of the adjacent element.

6. Refrigerating apparatus comprising in combination a cabinet and a plurality of refrigerating elements disposed side by side in the cabinet; each of the elements including a freezing compartment and each including a plurality of ducts for circulating refrigerant, spaced from one another lengthwise along its compartment, certain ducts of one element being in contact with the compartment of the adjacent element.

7. Refrigerating apparatus comprising in combination, a cabinet and a plurality of similar refrigerating elements disposed side by side in the cabinet; each of the elements including a freezing compartment and each including a plurality of ducts for circulating refrigerant spaced from one another

lengthwise along its compartments, the elements being assembled in the cabinet in staggered relation and with certain ducts of one element in heat exchange relation with the compartment of its adjacent element.

8. Refrigerating apparatus comprising in combination, a cabinet and a plurality of refrigerating elements disposed side by side in the cabinet; each of the elements including a freezing compartment, a plurality of ducts for circulating refrigerant in intimate thermal contact with the compartment and a plurality of ducts disposed remote from the compartment, the remote ducts in one element being placed in heat exchange relation with the compartment of the adjacent element.

9. Refrigerating apparatus comprising in combination, a cabinet and a plurality of refrigerating elements disposed side by side in the cabinet; each of the elements including duct means forming a freezing enclosure, part of the duct means of one element being so disposed as to cooperate with the duct means of the adjacent element in forming the freezing enclosure of said adjacent element.

10. Refrigerating apparatus comprising in combination, a cabinet and a plurality of refrigerating elements disposed side by side in the cabinet; each of the elements including duct means forming a freezing enclosure, part of the duct means of one element being interspersed between the duct means of the adjacent element and cooperating with the duct means of the adjacent element to form the freezing enclosure thereof.

11. Refrigerating apparatus comprising in combination, a cabinet and a plurality of refrigerating elements disposed side by side in the cabinet; each of the elements including a freezing compartment, duct loops surrounding the compartment and having portions in contact with the compartment, portions of the loops of one element being interspersed between those portions of the loops of the adjacent element which are in contact with the compartment associated with said adjacent elements.

12. Refrigerating apparatus comprising in combination, a cabinet and a plurality of refrigerating elements disposed side by side in the cabinet; each of the elements including a freezing compartment, duct loops surrounding the compartment and having portions in contact with the compartment, portions of the loops of one element being in heat exchange relation with the compartment of the adjacent element.

13. Refrigerating apparatus comprising in combination a cabinet and a plurality of refrigerating elements disposed side by side in the cabinet; each of said elements including a freezing compartment and each including a plurality of ducts for circulating refrigerant, certain ducts of one of said ele-

ments being in contact with a compartment of another of said elements.

14. Refrigerating apparatus comprising in combination a cabinet and a plurality of refrigerating elements disposed side by side in the cabinet; each of said elements including a freezing compartment and each including a plurality of ducts for circulating refrigerant, certain ducts of one of said elements being in contact with a compartment of another of said elements, and certain ducts of the last element being in contact with the compartment of the first element.

In testimony whereof I hereto affix my signature.

JESSE G. KING.
